UNITED STATES PATENT OFFICE

144,856

DESIGN FOR A CANDY DISH OR SIMILAR ARTICLE

Ada Lucille Jack, Los Angeles, Calif.

Application November 26, 1945, Serial No. 124,072

Term of patent 14 years

(Cl. D44—10)

To all whom it may concern:

Be it known that I, Ada Lucille Jack, a citizen of the United States, residing in the city and county of Los Angeles and State of California, have invented a new, original, and ornamental Design for a Candy Dish or Similar Article, of which the following is a specification, reference being had to the accompanying drawing, forming part thereof.

The figure is a perspective view of a candy dish or similar article embodying my new design.

I claim:

The ornamental design for a candy dish or similar article, substantially as shown.

ADA LUCILLE JACK.
